UNITED STATES PATENT OFFICE.

FRANK FREDERICK SIMONS, OF HARMONY, PENNSYLVANIA.

CRAFT-PROPELLION MECHANISM.

1,355,110.

Specification of Letters Patent.

Patented Oct. 5, 1920.

Application filed November 5, 1918. Serial No. 261,222.

To all whom it may concern:

Be it known that I, FRANK FREDERICK SIMONS, a citizen of the United States of America, residing at Harmony, in the 5 county of Butler and State of Pennsylvania, have invented certain new and useful Improvements in Craft-Propulsion Mechanism, of which the following is a specification.

10 The primary object of the invention is the provision of means of locomotion especially adaptable for aircraft of different forms as well as being serviceable upon vehicles and boats, including submarines, an 15 even traveling movement being obtained without the employment of rotary propellers.

20 A further object of the invention is to provide motor driven operating planes positioned laterally of an aircraft for moving the craft at desirable speeds through the air and eliminating all forward and rear propellers, the craft being easily steered and manipulated by reason of the compact arrangement of the mechanism as well as providing more room for the occupants of the 25 craft and with unobstructed space at the rear end portions thereof for taking observations as well as firing upon the enemy.

30 A still further object of the invention is to provide propulsion means for aeroplanes that is positive in its operation, simple in construction and not liable to get out of working order or require repairs while 35 the same is capable of overcoming great resistance in the line of flight when in use and is especially serviceable upon war crafts such as bombing planes.

With these general objects in view and 40 others that will appear as the nature of the invention is better understood the same consists in the combination and arrangement of parts hereinafter fully described in connection with the accompanying drawings in 45 which like reference characters designate corresponding parts throughout the several views.

In the drawings,

Figure 1 is an elevational view of a bi-plane provided with my invention,

Fig. 2 is an enlarged horizontal sectional view taken through the mounting frame of the propulsion mechanism between the planes or main aerofoil of the aircraft, parts 55 being illustrated by dotted lines,

Fig. 3 is a side elevation thereof,

Fig. 4 is an enlarged side elevation of the operating connections of the propulsion mechanism,

Fig. 5 is a top plan view of the same, 60

Fig. 6 is a perspective view of portions of the propulsion mechanism,

Fig. 7 is a central longitudinal sectional view through one of the propellers or ailerons, 65

Fig. 8 is a transverse sectional view through one of the blades in its horizontal inoperative position, illustrating by dotted lines the vertical operative position thereof,

Fig. 8^A is a perspective view of an automatic locking means for the blade, a slightly different form of blade being illustrated, 70

Fig. 9 is a top plan view thereof,

Fig. 10 is an enlarged longitudinal sectional view of the same. 75

Figs. 11, 12 and 13 are transverse sectional views thereof.

Fig. 14 is a top plan view of a combined guide and locking means for the blades illustrating by full and broken lines one 80 of the blades at its opposite extremities of travel.

Fig. 15 is a sectional view thereof with the blade illustrated in its intermediate position, and 85

Fig. 16 is a detail view of a portion of the blade with the guide shown in section.

My invention being designed for the propulsion of different forms of craft traveling either upon or beneath the surface of the water or through the air or upon the ground, is herein illustrated installed upon an aircraft, it being understood that substantially the same structural embodiment of the invention are adaptable for the other 95 forms of craft.

Such aircraft, above noted, is of the bi-plane form having a fuselage 10 with a transverse upper plane or main aerofoil 11 and outwardly projecting lower planes or 100 aerofoils 12 connected to the upper plane by posts 13. A wheeled chassis 14 is provided beneath the fuselage as well as a strut 15 while a vertical rudder 16 forms a portion of the empennage in connection 105 with opposite horizontal rudders 17. The craft propulsion mechanism hereinabove specifically described is positioned substantially centrally beneath the main upper aerofoil 11 leaving the fore and aft por- 110

tions of the fuselage 10 for the manipulator of rapid fire guns 18 from the adjacent wells 19 provided in the fuselage 10.

A frame is provided beneath the aerofoil 5 11 including upright posts 20 connected between the aerofoil 11 and a deck portion 21 of the fuselage 10 while pairs of inwardly curved side pieces 22 are connected between the corner posts 20.

10 A motor 23 of any form such as an explosive motor is positioned within the fuselage 10 at any desirable point operatively connected by means of a sprocket chain 24 with a gear 25 mounted upon an axle 26 journaled by means of a bracket 27 adjacent the forward end of said frame. A pinion 28 upon the rear end of the axle 26 is in constant mesh with a bevel gear 29 having a shaft 30 provided with oppositely projecting 15 cranks 31 and 32 above and beneath the pinion 29.

The active propulsion of the craft is accomplished by means of blades or ailerons 33 provided in one or more pairs and adapted 25 for operation by the said cranks for forward and rearward movement after the manner of the oars of a boat in the rowing operation.

The installation of the invention herein illustrated includes two pairs of blades the 30 forward pair being designated 33 and a rearward pair 33' operatively connected to the cranks 31 and 32 respectively. The formation and operation of each pair of blades is substantially identical but so timed as to be 35 opposite in movement during operation.

A swinging arm 34 is provided for each blade 33 pivoted upon opposite upright rods 35 secured between the side pieces 22 while braces 36 connect the rods 35 together above 40 and beneath the point of attachment of said arms 34.

The blades 33 and 33' are longitudinally journaled upon rods 37 axially secured through the arms 34 so that said blades may 45 assume either a horizontal inoperative or a vertical operative position under the control of the automatic tripping means hereinafter set forth.

Inward extensions 38 are provided for the 50 arms 34 pivotally connected by means of links 39 with a head 40 slidably upon a guide wire 41 mounted longitudinally of the frame and supported by any convenient portion thereof.

55 A connecting rod 42 pivotally connects the free end of the crank 31 with the head 40, whereby during the revolving of the gear 29, the rod 42 and head 40 are reciprocated for swinging the arms 34 forwardly and rearwardly together with the blades pivotally mounted upon the arms. The head 40 provided parallel pins 73 having flattened ends 74 slidably mounted upon the wire 41 and connected by a spring 75 between the ends 60 74. The links 39 are pivoted upon one of

said pins 73 while the connector 42 is pivoted to the other pin 73. In this manner, the links and connectors are connected for operation in either direction by the head 40. The forward blades 33 are shown in their 70 horizontal inoperative positions in Figs. 1, 2, 3 and 6 of the drawings with the head 40 and connecting rod 42 at substantially the forwardmost limit of their strokes. It will be seen that when the blades 33 are so positioned, terminal extensions 43 of the rods 37 will engage brackets 44 upon upright side posts 45 outwardly of the side pieces 22, and acting as stops for any further movement of the blades 33 in an inwardly rearwardly direction. Upon turning the gear 29, the rod 42 and head 40 are moved rearwardly thereby swinging the arms 34 by means of the links 39 and extensions 38, swinging the horizontal blades 33 forwardly through 85 the air.

Angular trips 46 are carried at the outer free ends of the blades 33 adapted for engaging rearwardly projecting lugs 47 upon the forward post 20, which automatically 90 swing the blades 33 to their upright vertical operative positions. At this forward positioning of the blades 33, the terminal members 43 engage forward brackets 48 adjacent said forward post 20. The continued movement of the gear 29 forwardly moves the rod 42 and head 40 thereby drawing forwardly the links 39, rearwardly moving the arms 34 and the vertical blades 33. The said blades are provided with slightly concaved rear 100 faces 49 which during this rear movement of the blades fill with air resulting in a forward impulse to the aircraft. When the vertical blades 33 are nearing the rearward limit of their movements, the trips 46 engage lugs 47 upon the post 45, automatically 105 swinging the blades 33 to their horizontal positions for free return movement through the air.

In this manner, the blades 33 accomplish 110 a rowing action, feathering during the forward inoperative movement thereof and exerting great pressure against the air during the rearward movement of the blades for forcing the craft forward upon its course of 115 travel.

The rearward pair of blades herein designated as 33' operate in precisely the same manner as the forward blades 33, having their arms 34' provided with extensions 38' 120 pivotally connected by links 39' with a head 40' slidably mounted upon a guide wire 41' secured longitudinally of the mounting frame but upon a level beneath that of the wire 41. A connecting rod 42' pivotally 125 connects the free end of the crank 32 with the sliding head 40'. It will be seen that the opposite positioning of the cranks 31 and 32 at all times operate the rods 42 and 42' oppositely so that while the forward 130

blades 33 are performing their operative rear strokes, the rear blades 33' are recovering by moving forwardly positioned horizontally as heretofore noted. The continuous operation of the motor 23 thereby accomplishes the continuous rowing movements of the blades 33 and 33' it being understood that the blades 33' are provided with suitable trips 46 for automatically revolving the blades 33' upon engaging lugs 47" extending rearwardly from the post 45 and similar lugs 47'" forwardly projecting from the rear posts 20 of the frame. Any form of reciprocating power means may be provided for the connecting rods 42 and 42' while it will be also understood that only one set of blades such as 33 may be provided if desired, while a greater number than two sets of blades may be provided if the occasion requires and in the event the same will be coupled up with the source of power supply in any convenient manner. The arm 34 of each blade 33 is provided with opposite stops 50 for limiting the swinging of the blades 33 to their horizontal positions, preventing any further rotation of the blades while a similar projecting stop 51 upon the outer end of each arm 34 is engaged by the adjacent blade when the same assumes its operative vertical position. For purposes of smooth operation, one of the links 39 is preferably of single form while the other is double as best illustrated in Fig. 6 of the drawings.

35 A locking means is preferably provided for the blades 33 for insuring their horizontal position upon their return forward movement and their operative vertical position during the rearward movement thereof and this mechanism will now be described.

40 A blade 52 having the same operation as the aforementioned blades 33 and 33' also slightly different in contour is journaled upon a longitudinal shaft 53 axially secured through a cylindrical handle or frame 54 provided for the blade while an extension 55 projects from the arm 54 to be operatively connected to a source of power supply in the manner heretofore set forth. A projection 56 at the free end of the blade is also adapted to limit the forward and rear swinging movements thereof while an angular trip 57 carried by the blade is adapted to automatically shift the latter from its horizontal to its vertical position and vice versa. A guard 58 may be carried by the arm 54 surrounding and slightly spaced from the blade 52. A rectangular frame 59 is shiftably mounted transversely surrounding the arm 54 by means of projecting T-shaped brackets 60. A right angular locking plate 61 is pivoted as at 62 upon opposite sides of the arm 54 adjacent its outer end adapted for receiving a cross pin 63

within the angular sides of said plates when 65 the blade 52 is vertical.

Outwardly projecting ribs 64 are provided upon the free end of the arm 54 for engagement by the pin 63 in limiting the rotation of the blade 52. A two-part link 65 is provided for each of the plates 62 having their outer ends attached to said plates and their inner ends pivotally connected as at 66 centrally of the upper and lower sides of the frame 59. Positioning springs 67 are mounted upon the sides of the frame 59 between the link 65 and the bracket 60. By these means, when the outer ends of the frame 59 are normally positioned, the plates 61 will engage and hold the pins 63 when 75 the pins are vertical as well as the blades 52 while the plates 61 will also prevent a return movement of the pin 63 and blade 52 when said pin and blade are horizontal. A guide 68 is mounted upon the arm 54 having 80 slots 69 therethrough for the reception of the link 65.

It will be seen that when the blade 52 approaches the rear limit of its movement, one end of the frame 59 will engage a stop 90 70 carried by the framework 71 of the aircraft, which will shift the plates 61 to their released positions as shown in Fig. 9 of the drawings, thereby permitting the trip 57 which engages the lug 71 of the frame member 72 to throw the blade 52 to its horizontal position. The blade will then move forwardly, releasing the frame 59 which will lock the blade 52 horizontally until in a similar manner, the blade 52 will be released 95 at the forward limit of its travel, permitting the blade to swing to its operative vertical position by means of the forward engagement of the trip 57 and in which position the blade will be locked for its operative 100 rearward movement.

105 A positive rowing action is attained in this manner without liability of the blades 52 revolving in an undesirable direction during the propelling actuation of the said 110 blades.

115 The form of blade locking mechanism just described is equally serviceable for the blades 33 by mounting the mechanism upon the arm 34 thereof and all of which will be readily apparent. An aircraft provided with this means of propulsion may swiftly travel under the guidance of the pilot in any desired direction with an even and uniform motion.

120 A simple form of guide and rotation preventing means for the blades is illustrated in Figs. 14, 15, and 16 of the drawing in connection with a slightly different form of blade 80 having its arm 81 journaled in alignment with and upon the end of an operating lever 82 by means of a sleeve 83, the said lever being pivoted as at 84 and

adapted for movement by a connecting rod 85.

An arcuate guide consisting of two parallel sides 86 is provided with the arm 81 slidable longitudinally thereof, a rectangular shoulder 87 being provided upon the arm 81 for sliding within the guide in substantial contact with the opposite sides of the guide so that the rotation of the blade 80 is prevented during the swinging movement thereof. When the shoulder 87 passes within the enlarged ends 88 of the guide, the blade 80 is free to revolve a quarter turn which revolution is effected by means of a trip 89 carried by the arm 81. A stub 90 carried by the top of one of the ends 88 is engaged by the trip 89 at the termination of the power stroke of the blade 80 thereby turning the blade to its horizontal position for the return stroke. A finger 91 projects from the side of the opposite end 88 of the guard adapted for engagement by the upwardly bent end 92 of the trip 89 at the completion of the recover stroke thereby shifting the blade 80 to its vertical position for the next power stroke. A slot 93 of substantially 90° is provided in the sleeve 83 within which a pin 94 carried by the arm 81 is adapted to move, thereby limiting the rotation of the said arm and its blade 80 to the vertical and horizontal positions. It will be understood that the sides 86 hold the blade either vertical or horizontal during the shifting thereof and in whichever position the blade has been placed by its quarter turn within the ends 88.

What I claim as new is:—

1. Craft propulsion means comprising members having shiftable blades, operating means for such members, and automatic means associated with the swinging ends of the blades for feathering the blades at points adjacent their limits of movement in opposite directions.

2. Craft propulsion means comprising laterally positioned blades, means for swinging said blades longitudinally of the craft and means associated with the swinging ends of the blades for feathering the blades at points adjacent the limits of movements in opposite directions.

3. Craft propulsion means comprising a pair of opposite blades, means adapted for swinging said blades in arcuate paths and means associated with the swinging ends of the blades adapted for partially revolving the blades at points adjacent the limits of movement in opposite directions.

4. Propulsion means for an aircraft comprising laterally positioned blades adapted for simultaneous to-and-fro motion; power operating means operatively connected to the said blades and tripping means associated with the outer swinging ends of the

blades for automatically shifting the blades from operative to inoperative positions and vice versa when the blades reach their limits of movement in opposite directions.

5. Propulsion means for aircraft comprising laterally projecting arms swingingly mounted thereon, operating means for said arms carried by the craft, air-engaging blades journaled for partial rotation upon the said arms and means coöperating with the swinging ends of said blades at points adjacent their limits of movement in opposite directions for partially rotating the blades.

6. Propulsion means for aircraft comprising laterally projecting arms swingingly mounted thereon, operating means for said arms carried by the craft, air-engaging blades journaled at the free ends of said arms, movement-limiting means for the blades and automatic revolving means adapted to be engaged by the swinging ends of the blades whereby the latter are vertically positioned during the rearward stroke thereof.

7. Propulsion means for aircraft comprising laterally projecting arms swingingly mounted upon the craft, power means upon the craft adapted for moving said arms simultaneously forwardly and rearwardly, blades journaled at the free ends of said arms adapted for vertical positioning during the rearward swinging movement of the arms and for horizontal arrangement during the forward movement thereof, and means carried by the craft adapted to be engaged by the swinging ends of said arms for changing the positions of the blades.

8. Propulsion means for craft comprising laterally projecting arms swingingly mounted upon the craft, power means upon the craft adapted for moving said arms simultaneously forwardly and rearwardly, blades journaled for partial rotation at the free ends of said arms, means adapted for limiting rotation of said blades to a horizontal and vertical arrangement and automatic tripping means for the blades adapted to be engaged by the blades during the forward and rearward movement thereof whereby the latter are positioned in their operative vertical arrangement during their rearward movements and horizontally during the forward movements of the blades.

9. Propulsion means for craft comprising laterally projecting arms swingingly mounted upon the craft, power means upon the craft adapted for moving said arms simultaneously forwardly and rearwardly, blades journaled at the free ends of said arms adapted for vertical positioning during the rearward swinging movement of the arms and for horizontal arrangement during the forward movement thereof, locking means upon said arms whereby said blades

- are secured in their vertical and horizontal positions during the to-and-fro movements of the blades, and automatic controlling means for said locking means.
- 5 10. Propulsion means for craft comprising laterally projecting arms swingingly mounted upon the craft, power means upon the craft adapted for moving said arms simultaneously forwardly and rearwardly, 70
- 10 blades journaled for partial rotation at the free ends of said arms, means adapted for limiting rotation of said blades to a horizontal and vertical arrangement, automatic tripping means for the blades whereby the 75
- 15 latter are positioned in their operative vertical arrangement during their rearward movements and horizontally during the forward movements of the blades, locking means upon said arms whereby said blades 80
- 20 are secured in their vertical and horizontal positions during the to-and-fro movements of the blades, and automatic controlling means for said locking means.
11. Propulsion means for aircraft comprising a frame upon the craft, laterally projecting arms pivoted upon said frame, a longitudinal guide wire centrally of the frame, a head slideable upon said wire, operative connections between said head and 90
- 25 arms, power-driven reciprocating means operatively connected to said head and blades operatively journaled upon the free 95
- 30 ends of said arms.
12. Propulsion means for aircraft comprising a frame upon the craft, laterally projecting arms pivoted upon said frame, a longitudinal guide wire centrally of the frame, a head slideable upon said wire, operative connections between said head and 100
- 35 arms, power-driven reciprocating means operatively connected to said head, blades journaled for partial rotation at the free outer ends of said arms adapted for vertical positioning during the rearward movement 105
- 40 of the arms and horizontal positioning during the forward movement thereof and automatic means adapted for shifting said blades from their vertical to their horizontal positions substantially at the limit 110
- 45 of the rearward travel of the blades.
13. Propulsion means for aircraft comprising a frame upon the craft, laterally projecting arms pivoted upon said frame, a longitudinal guide wire centrally of the 115
- 50 frame, a head slideable upon said wire, operative connections between said head and arms, power-driven reciprocating means operatively connected to said head, blades journaled for partial rotation at the free 120
- 55 outer ends of said arms adapted for vertical positioning during the rearward movement of the arms and horizontal positioning during the forward movement thereof, automatic shifting means adapted for shifting 125
- 60 said blades from their vertical to their horizontal positions substantially at the limit of the rearward travel of the blades, means for locking said blades in their vertical and horizontal positions and automatic actuating means for the said locking means. 70
14. Propulsion means for aircraft comprising pairs of laterally projecting arms horizontally swingingly mounted upon the craft, air-engaging blades horizontally journaled at the outer ends of said arms 75
- adapted for vertical and horizontal positioning during operation, reciprocating means operatively connected to said arms adapted for swinging the pairs of arms to-and-fro in opposite directions when the 80
- blades are oppositely positioned and means associated with the swinging ends of the blades to cause a partial rotation thereof adjacent the limit of movement of the blades in opposite directions. 85
15. Propulsion means for aircraft comprising a forward and rear pair of arms pivoted for horizontally swinging laterally of the craft, power means operatively connected to said arms adapted for imparting to-and-fro movements thereto simultaneously in opposite directions, air-engaging blades horizontally journaled for partial rotation at the outer free ends of said arms and means associated with the swinging 90
- 95 ends of the blades to cause a partial rotation thereof adjacent the limit of movement of the blades in opposite directions.
16. Propulsion means for aircraft comprising a forward and rear pair of arms pivoted for swinging laterally of the craft, power means operatively connected to said arms adapted for imparting to-and-fro movements thereto simultaneously in opposite directions, air-engaging blades journaled for partial rotation at the outer free ends of said arms, means adapted to be engaged by said blades at their limits of movement in opposite directions automatically to shift said blades to their vertical positions 100
- 105 prior to the rearward movements thereof and to their horizontal positions for traveling forwardly. 110
17. Propulsion means for aircraft comprising a forward and rear pair of arms pivoted for swinging laterally of the craft, power means operatively connected to said arms adapted for imparting to-and-fro movements thereto simultaneously in opposite directions, air-engaging blades 115
- 120 journaled for partial rotation at the outer free ends of said arms, means adapted to automatically shift said blades to their vertical positions prior to the rearward movements thereof and to their horizontal positions for traveling forwardly, rotation limiting means for the blades and automatic locking means for said blades adapted for holding the latter in their vertical positions during rearward movement and in 130

horizontal positions during the forward travel thereof.

18. Guide means for propelling blades comprising an arcuate rack having parallel sides and enlarged ends, a blade having its arm projecting through said rack, a rectangular shoulder upon said arm adapted for sliding between the sides of said rack and for turning a quarter revolution within the opposite ends thereof and means adapted for turning the blade a quarter revolution in opposite directions when said shoulder is positioned in the end portions of the guide.

19. Guide means for propelling blades comprising an arcuate rack having parallel sides and enlarged ends, a blade having its

arm projecting through said rack, a rectangular shoulder upon said arm adapted for sliding between the sides of said rack and for turning a quarter revolution within the opposite ends thereof, means adapted for swinging the blade to and fro with said shoulder in the guide, tripping connections between the arm of the blade and the end portions of the guide for automatically revolving the blade from its vertical to its horizontal position and vice versa when said shoulder is positioned within said end portions and means adapted for limiting the rotation of the blade.

In testimony whereof I affix my signature.
FRANK FREDERICK SIMONS.
